UNITED STATES PATENT OFFICE.

FERNANDO HALTERMAN, OF OSO, WASHINGTON.

CABLEWAY.

1,080,827.

Specification of Letters Patent.

Patented Dec. 9, 1913.

Application filed January 16, 1913. Serial No. 742,471.

To all whom it may concern:

Be it known that I, FERNANDO HALTERMAN, a citizen of the United States, and resident of the town of Oso, in the county of Snohomish and State of Washington, have invented certain new and useful Improvements in Cableways, of which the following is a specification.

My invention relates to cableways, particularly those which are used for logging purposes, and it comprises the novel parts and combinations of parts which will be hereinafter described and particularly pointed out in the claims.

The object of my invention is to provide a type of cableway particularly adapted for logging where the logs are of the large size found upon the Pacific coast, with which superior results may be secured without materially increasing the cost of the apparatus and under which plan the apparatus may, in some respects, be made lighter and more flexible in use.

In the accompanying drawings I have shown my present preferred form.

Figure 1 shows, in plan, a cableway made in accordance with my invention. Fig. 2 shows the same apparatus in elevation. Fig. 3 shows, in elevation, a cableway of like character, except that the outward run of the haul-back line is carried alongside the trackway cables. Fig. 4 shows the carriage and trackway members on a larger scale, omitting refinements of detail in design. Figs. 5 and 6 are, respectively, side and edge elevations of the auxiliary carriage for the snubbing lines. Fig. 7 shows the carriage construction for a single cable trackway. Fig. 8 shows the snubbing line carriage in edge view.

My invention is particularly designed for use in logging, although it possesses features which well adapt it for other uses. I will, however, describe it as employed in logging, it being understood that it may be employed for other purposes and that my invention lies in the apparatus and the system, and not alone in the use to which it is put.

The usual practice in operating a cableway for hauling out logs, employs the cableway, as set in any one position, for removing the logs lying upon a relatively narrow strip, such strip extending for a distance of approximately seventy-five feet at each side of the cableway. While logs may be drawn

in from a greater distance than this, if the logs are small, it is seldom, with the large logs found in the Pacific coast section of the country, that a greater distance is covered at one setting of the cableway. One reason for this limitation, is that hauling from a greater lateral distance brings an excessive strain upon the trackway cables. This is due largely to the fact that it requires, quite generally, a much greater pull to haul a log out of the brush and débris of a clearing, than it does to bring it in after it has been brought under the cableway. The lateral haul, except for a short distance near the cableway, is a straight drag over the ground, with all kinds of probable resistances due to engagement with roots, stumps and brush, as well as the always present digging into the earth and the friction due to the weight of the log. When the log reaches the cableway, its front end is always carried mostly, or entirely, clear of the ground, and at times, the entire log is carried upon the cableway. The result is that it will slide easily over any obstruction and the power required to bring it in along the cableway is relatively small. It is not difficult to provide engine power and hauling line sufficiently strong to easily overcome the greatest of these resistances, but to provide trackway cables of sufficient strength, means excessively heavy cables, which means excessive costs and difficulties in moving and setting up. The inability to work at any great distance from the line of the cableway, also means more frequent moving.

By my invention I provide snubbing lines which may be brought into use whenever desired, to take care of the side or lateral strains upon the trackway cables, whenever pulling in from the side. By this expedient I so strengthen the trackway cables that they are capable of standing any lateral strain which the hauling line is capable of exerting, therefore making it possible to haul from any lateral distance to which it is expedient to take out logs, without preparing a trackway therefor. This will reach as far as five hundred feet and may, in some cases, much exceed this.

In the drawings, 15 represents the head mast and 16 the tail mast.

1, 1, represent the two trackway cables. I have shown two cables used as trackways, for the reason that in this way smaller ca-

bles may be used, these being easier to handle than larger cables.

I prefer that the trackway cables proper, terminate at clevises 10, or other means by 5 which the cables may be broken near the head mast, so that the carriage may be easily removed. Extensions 11 extend over suitable supporting guides upon the head mast and are secured to tightening and take- 10 up means, interposed between the mast and the anchorages 13, such means, as shown, consisting of blocks and line, 12. When putting up or taking down the cables, these will facilitate the work.

15 At the tail mast, 16, the cables 1, 1, are shown as extended to the ground and secured to stumps 14, or other suitable anchorages. Guy lines 17 are also provided as needed.

The carriage 4 may be of any suitable 20 construction. This has wheels 40, which run upon the trackway cables 1, and carries, or has secured thereto, guide pulleys 22 and 34 for the accommodation respectively of the haul line and the haul-back line.

25 The engine should have at least two drums, 20 and 21, drum 20 carrying the haul line 2 and drum 21 carrying the haul-back line 3. The haul line passes over a guide 23 carried by the head mast and thence to the 30 carriage 4 and over the guide sheave 22.

As shown in Figs. 1 and 2, the haul-back line passes about guide sheaves 30 which are so placed as to conduct the haul-back line off to one side of the cableway and 35 thence out along a line substantially parallel the cable way and then back to a point near the tail mast. This point may be somewhat short of the tail mast, as shown at 31. After passing about a course of this kind to the 40 vicinity of the tail mast, the haul-back line is carried over a guide pulley or sheave 34, carried by the carriage, thence to a guide sheave 32, which is shifted in position to suit the point from which logs are to be 45 taken. This sheave 32 will be shifted to any point within the area of the tract covered by the cableway from any one position. This will include a strip of considerable possible size extending even back of or beyond 50 the tail mast. The end of the haul-back line is secured to the end of the haul line, in order to be able to quickly take this back to the point where a log is to be taken from.

Passing the haul-back line through a 55 guide sheave upon the carriage and then through a guide sheave upon the ground, gives three parts of the haul-back line which may be depended upon to hold the carriage against travel under the strain of the haul line. This makes it possible to strain the 60 haul line up to its limit without advancing the carriage, should this be necessary in hauling out a log to the cableway. At the same time, the haul-back line may be kept 65 light and therefore easy to handle.

The snubbing lines which I employ to take the side strain upon the cables, developed when hauling in from the side, are attached as follows: Upon the trackway cables are mounted, preferably, two auxiliary carriages 70 5, 5, these being placed one at each side of the carriage 4. These are separate from the main carriage 4, but are attachable thereto in such manner as to be moved thereby along the cableway when this is desired. At 75 times these carriages and their attached snubbing lines would not be needed and they may be left upon the cableway respectively near the head and tail masts.

To each carriage 5, 5, is secured a line of 80 such length that it may be carried out laterally a reasonable distance and secured to a stump, tree or other object to resist the side strain put upon the carriage when hauling in a log from the side. At times, for 85 small or moderate sized logs, only one of these snubbing lines need be used, but for large logs I prefer to use both.

A preferred form of carriage for the snubbing lines is shown in Figs. 5 and 6. This 90 comprises a frame 53, which should have considerable strength and be provided with means, as eyes 52, to which the lines may be attached at each side, and wheels 50 adapted to run above the cableway lines 1, 1, and 95 wheels 51 adapted to lie beneath the trackway cables. The snubbing lines 55 should be attached to these carriages so that they may be detached and shifted to the other side, as by clevis 54.

The arrangement shown in Fig. 3 differs 100 from that described, only in providing guide supports for the outgoing part of the haul-back line, alongside of the trackway cables 1. The carriage as shown in Fig. 4, has a 105 guide sheave 33 for the haul-back line and the tail mast has a guide sheave 35.

In Fig. 7 I have shown a form of construction of carriages adapted for use on a single cable trackway. The main carriage 110 4 has a single set of wheels 40 running upon the trackway cables and wheels 22 and 34 for the haul line and haul-back line, respectively. In this case the cableway guide or auxiliary carriage which is used with the snubbing line, consists of a single wheel 50 and its frame 56, the latter being made wide beneath the trackway cable to permit 115 its swinging toward either side, without necessity for any change.

It is immaterial, in my invention, that 120 the exact means for attaching the snubbing lines to the cableway as herein shown, be used. The form of this attachment would be different in a two cable cableway from 125 that for a single cable cableway, as has been shown. It may also vary for the same type of cableway.

What I claim as my invention and desire to secure by Letters Patent is:

1. The combination with a cableway of a snubbing line having traveling engagement by one end with the cableway, the other end being free and securable at will 5 to any fixed object.
2. The combination with a cableway of a plurality of snubbing lines secured by one end to and extendable laterally from the cableway adjacent and at each side of the carriage, the other ends of said snubbing lines being free and securable at will. 10
3. In a cableway, in combination, a trackway cable, a carriage thereon, a haul line, a haul-back line, and a snubbing line secured by one end to hold the carriage, the other end of the snubbing line being free and adapted to be secured wherever desired. 15
4. In a cableway, in combination, a trackway cable, a carriage thereon, a haul line, a guide for the haul line carried by the carriage, and a snubbing line extending laterally from the carriage. 20
5. In a cableway, in combination, a cable trackway, a carriage thereon, a haul line, a guide for said haul line carried by the carriage, and snubbing lines having guides adapted to travel upon the cable trackway and to be placed alongside the carriage. 25
6. The combination with a cableway having a haul line adapted to be carried out laterally from the carriage, of a snubbing line secured adjacent the carriage and adapted to be secured laterally of the cableway and in a direction to counteract the side 30 pull of the haul line while bringing a load up to the cableway.
7. The combination with a cableway, a carriage thereon, a haul line and a guide, for the haul line carried by the carriage, of two cable guides adapted to travel upon the cableway, one at each side of the carriage, and a snubbing line secured to each of said cable guides. 40
8. The combination with a log-hauling cableway comprising a trackway cable, a carriage adapted to travel upon said trackway, a haul line, a haul-back line, of an auxiliary carriage running upon the trackway cable and having wheels engaging the cable from 45
- above and from below and a snubbing line secured to said auxiliary carriage. 50
9. The combination with a log hauling cableway having a plurality of trackway cables, a carriage traveling upon said cables, a haul line having guiding support upon said carriage, of an auxiliary carriage having wheels engaging the trackway cables from opposite sides, and provided with means for securing a line to opposite sides thereof, and a snubbing line adapted to be secured to either side of said auxiliary carriages. 55
10. The combination with a cableway a carriage thereon and a haul line having guiding support from said carriage, of an auxiliary carriage adapted to travel upon the cableway, and means for securing a snubbing cable to either side of said auxiliary carriage. 60
11. The combination with a cableway comprising a trackway cable, a carriage running thereon and having guides for a haul line and for a haul-back line, a haul line extending to the carriage and over its guide thereon, a guide for the haul-back line at the outer end of the trackway, a guide for the haul-back line adapted to be shifted to any desired point, a haul-back line passing through said outer or distant guide, then about the guide upon the carriage and then about said movable guide and thence to the end of the haul line. 65
12. In a cableway, in combination, a trackway cable, a carriage thereon having a guide for a haul line, a haul line, a haul-back line, two distant guides for the haul-back line, and a guide for the haul-back line carried by the carriage and placed in the course of said line between said distant guides, whereby said haul-back line is connected with the carriage by a loop. 70
- In testimony whereof I have hereunto affixed my signature at Oso, Washington, this 9th day of January, 1913.
